UNITED STATES PATENT OFFICE.

EUGENE LENNON, OF SAN DIEGO, CALIFORNIA.

APPARATUS FOR OPERATING DOORS AND GATES.

Application filed July 22, 1925. Serial No. 45,369.

The invention is designed to provide means of simple construction and efficient operation for opening and closing gates or doors, such as doors of garages, by the passage of the automobile, and the invention consists in the features and combination and arrangement of parts hereinafter described and particularly pointed out in the appended claims.

10 In the drawings:

Figure 1 is a diagrammatic plan view of the apparatus.

Fig. 2 is a side elevation.

15 Figs. 3, 4, 5, and 6 are diagrammatic plan views.

Fig. 7 is a detail view of a supporting frame work or post for part of the operating connections.

Fig. 8 is a detail view of one of the door 20 posts or shafts.

Fig. 9 is a detail of the connection between one of the operating rods and the operating segment.

Fig. 10 is a detail view of means for controlling one of the sections of the door or gate.

Fig. 11 is a detail view of the sleeve.

Each door is mounted on a vertical rotatable post 1. At its upper end each post has 25 connected thereto operating mechanism consisting of rods 1^a, 1^b, extending from arms or segments 2, 2^a. These rods are connected respectively to one end of sleeves or barrels 3, 3^a. These sleeves receive at their other 30 ends slidably the rods 4, 4^a having heads 5, 5^a, at their inner ends with springs 6, 6^a interposed between said heads and the ends of the sleeve. These rods 4, 4^a are operated 35 through links 15 by levers 7, 7^a, pivoted at 40 8, 8^a on pins guided in slots 9 in fixed standards 10.

The ends of the pins bear on springs 11 seated in the standards so that the pivots together with the levers can have movement 45 up and down and the levers have pivotal movement about the pins 8, 8^a. The lower ends of the levers are pivotally connected to the stirrups or treadles 12, 12^a which are pivotally mounted in suitable bearings as 50 shown.

In the drawings I have marked a line 55 x—x on each of the views indicating the normal center position of the sleeve 3, 3^a, when the doors are closed and all the parts are in normal position, and the amount of movement of the sleeve under different

actions can be judged from the position of the sleeves in the several diagrams relative to these lines x—x.

In the operation of the apparatus suppose the vehicle moves in the arrow direction in Fig. 3, the effect will be to draw upon the rod 4 and the head 5 thereon will be moved leftward and through the spring 6 the sleeve 3 will be pulled leftward and 60 through the rod 1^b the door post will be given a quarter turn to open through an angle of 90 degrees. As soon as the wheel passes over the treadle 12 said treadle will 65 rise under the action of the springs 11 which return the parts, lever and left hand rod to normal position, leaving the door in its open position.

This normal position of the sleeve is 70 shown in Figs. 1 and 2.

The action above described has not affected the right hand set of connections except taking up the lost motion space or slack in the sleeve 3^a as in Fig. 3, and bringing the spring 6^b against the head 5^a, but 75 the rod 4^a, lever 7^a and stirrup are not affected. When, however, the wheel of the vehicle continuing in the arrow direction, Figs. 3 and 4, passes over and depresses the stirrup 12^a towards the right, it swings the 80 lever 7^a at its upper end leftward and pushes on the rod 4^a which thus through its head 5^a will press on the spring 6^b, push rod 1^a leftward, and this through the segment will 85 rotate the vertical shaft and close the door as 90 shown in Fig. 4. After the vehicle passes away from the stirrup 12^a, said stirrup will rise under the action of the springs at 11^a, 95 acting on the connections and the connections at the right will assume normal position shown in Fig. 1, ready to act when the vehicle moves from right to left. This action of the parts is shown in Figs. 5 and 6, 100 but need not be described in detail further than to say that it is in reverse order to that above described in connection with Figs. 3 and 4, the direction of movement of the vehicle being indicated by the arrow.

The mechanism above described is disclosed herein as an example of one way 105 in which my invention may be carried into effect.

Instead of the segments 2, 2^a arms may radiate from the vertical posts, of the doors, and the rods 1^a, 1^b may be directly 110 connected to these arms.

Further instead of the sliding pivots 8,

8^a these may be non-sliding and the necessary play to accommodate the movement of the stirrups may be secured by a slotted lower end of the levers 7, 7^a engaged by 5 the stirrups.

- In the form shown the rods 1^a 1^b may be connected with the segments by pivoted links, the pivots of which allow movement of the links relative to each other in one 10 direction but not in the other, so that movement of the rods 1^a, 1^b can be communicated by either a pull or a push. These links are shown in Fig. 9 at 13, and they have projections 14 which resist breaking of the joint 15 in one direction. The rods 4, 4^a are pivoted to the links 13 to accommodate the rise and fall of the levers 7, 7^a. The rotatable shafts or posts of the doors are provided with ball 20 bearings.
- 20 The doors may be provided with extra sections as at 16, Fig. 10 pivoted to the main sections and controlled by a pin or roller running in a fixed cam way 17 by which this section 16 folds into the position 25 shown in Fig. 10 when the door is opened, and moves to closed position when the door is shut.

I have described only one set of connections. These will answer when a single door 30 is to be operated, but where double doors are to be dealt with, these connections are duplicated and Fig. 1 shows this organization.

Any suitable bracing may be employed 35 for the structure.

The levers 7 may be pivoted to divide their movement equally on opposite sides of a vertical plane.

I claim:

- 40 1. In combination in apparatus for opening and closing doors, a treadle on each side of the door, a lever extending upwardly from each treadle and pivotally connected to the upper part of said treadle, a yielding support for said levers, said levers being pivoted intermediate of their height to said support, and connections from the upper ends of the levers to the doors, said connections each including a sleeve, a rod connecting one end of the sleeve with the door, a rod connected with the upper end of the lever and slidably connected with the sleeve, and having a headed end within the sleeve, and springs spaced apart within the sleeve, and arranged between the said headed end of the rod and the ends of the sleeve, substantially as described.

2. In combination in apparatus for open-

ing and closing doors, a treadle on each side of the door, a lever extending upwardly 60 from each treadle and pivotally connected to the upper part of said treadle, a yielding support for said levers, said levers being pivoted intermediate of their height to said support, and connections from the upper ends 65 of the levers to the doors, said connections including slack motion means whereby when the connections on one side of the door are operated to open or close the same, the connection on the other side of the door will 70 perform its lost motion action, substantially as described.

3. In combination with a swinging door, a treadle on each side thereof to be operated by the vehicle approaching or departing 75 from said door, and a connection between each treadle and the door, each connection comprising a sleeve, a rod connecting said sleeve with the door, and a rod between the sleeve and the treadle and slidable in the 80 sleeve, said last mentioned rod having a headed end with a spring between it and the outer end of the sleeve, and a second spring at the inner end of the sleeve, said springs being spaced apart for the slack 85 movement of the headed end of the rod between them, said springs cushioning both the opening and closing of the door, said springs also forming a part of the power transmitting connections between the treadles and 90 the door, each treadle because of the slack motion connection afforded by the sleeve with its spaced apart springs remaining in normal position when the treadle on the 95 opposite side of the door is operated, substantially as described.

4. In combination, a door, a rotary post carrying the door segments at the top of the post, a connection extending from each segment, one on each side of the door, a sleeve in each of said connections having springs therein with a space between them, each of said connections including a rod having a headed end working in the space between the springs and a rod connection 100 with the inner end of the sleeve and with one of the segments, and treadles with connections to the headed rod, each treadle because of the slack motion connection afforded by the sleeve with its spaced apart 105 springs remaining in normal position when the treadle on the opposite side of the door is operated, substantially as described.

In testimony whereof, I affix my signature.

EUGENE LENNON.
